UNITED STATES PATENT OFFICE.

JOHN MCKANE, OF LONDON, ENGLAND.

DESIGN FOR WALL PAPER OR A SIMILAR ARTICLE.

Application filed March 21, 1925. Serial No. 12,808. Term of patent 7 years.

To all whom it may concern:

Be it known that I, JOHN MCKANE, a subject of the King of Great Britain, residing at London, in the country of England, have invented a new, original, and ornamental Design for Wall Paper or Similar Article, of which the following is a specification, reference being had to the accompanying drawing, forming part thereof.

The figure is a plan view of a sheet of wall-paper showing my new design.

I claim:

The ornamental design for wall paper or a similar article as shown.

JOHN MCKANE.
